UNITED STATES PATENT OFFICE.

GEORGE L. PIERCE, OF BROOKLYN, NEW YORK, ASSIGNOR TO A. G. SPALDING & BROS.,
OF NEW YORK, N. Y., A CORPORATION OF NEW JERSEY.

PLAYING BALL.

Application filed April 19, 1928. Serial No. 271,210.

The invention relates to playing ball of the type in which an inflatable rubber bladder is inclosed in a case or cover of leather or similar material, and more especially 5 to the type in which the bladder has a valved inflating nipple which has screw-threaded engagement with a bushing or thimble secured to the cover.

The principal object of the present invention is to provide a structure by which the bushing and inflating nipple may be located 10 on the line of a seam joining separate pieces of the cover material.

The invention is of particular importance 15 in connection with playing balls in which a seam lies at the point directly opposite the cover opening by which the bladder is inserted, as it is advantageous in some cases to locate the inflating stem exactly opposite 20 the cover opening in order to give the ball perfect playing balance.

The invention is also applicable in other 25 locations, since the principle of placing the inflating stem on a seam avoids the weakening of the cover which results from punching 30 a hole in the middle of a piece of cover material.

My invention provides means for locating 35 the inflation device directly in line with the seam; that is, in a position intersecting the seam and in a manner which does not weaken the seam but on the contrary provides for substantial reinforcement of the seam and casing adjacent the inflation device. A 40 principal feature of the invention structure is the provision of a filler piece which substantially bridges the seam and affords a proper base for receiving and retaining the inflation bushing or thimble at a point directly in line with or intersecting the seam, 45 opposite the lace opening.

The characteristics and advantages of the 50 invention are further sufficiently explained in connection with the following detail description of the accompanying drawing, which shows representative embodiments. After considering these examples, skilled persons will understand that many variations may be made without departing from the principles disclosed, and I contemplate 55 the employment of any structures that are properly within the scope of the appended claims.

Fig. 1 is a plan view of a ball of the class 55 above referred to, from the lace opening side.

Fig. 2 is a plan view from the opposite side of the ball showing the invention structure.

Fig. 3 is a section at 3—3, Fig. 2.

Fig. 4 is a similar section of a slightly 60 modified structure.

Fig. 5 is a section at 5—5, Fig. 2, representing the structure of either Fig. 3 or Fig. 4.

The ball cover or casing C consists usually 65 of an outer layer, or cover proper, L, usually of leather, and a lining M, usually of canvas. The casing is made in a plurality of gores or sections such as 1, the adjacent 70 edges of which are turned inward and secured by stitching, forming seams 2. These seams project substantially inward at the inner surface of the cover as shown in Figs. 3 and 4. At one side of the ball is the usual lace opening structure 3 to permit insertion 75 of the bag or bladder 4, Fig. 5. At the side directly opposite the lace opening the casing usually has a seam 2^a. The bladder 4 as provided for balls of this class, has at one 80 side an inflation nipple 5 and a bushing or thimble has heretofore been inserted in one of the gores or sections 1^a, at the side of the bag opposite the lace opening; and because 85 of the fact that no means has heretofore been provided for locating this bushing directly in line with or in a position intersecting the seam such as 2^a, it has been inserted through one of the sections or gores such as 1^a, at a point close to but at one side of the seam. 90

I provide a casing inflation fitting or bushing structure which in itself is substantially like that disclosed in Patent No. 1,618,994, March 1, 1927 to myself and Henry V. Rau, comprising a bushing or thimble 10, internally screw-threaded and having at the inner end a flange 11 with opposite flat sides 12. The bushing is secured to a patch 13 of leather or other suitable material by inserting it through an opening in the bag and placing 100 a washer 14 over the neck of the bushing. The washer has prongs 15 which are forced through the leather patch and are then located adjacent the flat sides 12 of flange 11. The upper end of the bushing neck is 105 then "spun" or pressed over against the washer to form a flange 16.

To provide for properly attaching the bushing structure to the casing directly in line with the seam, a hole is cut through 110

the casing and through the seam 2^a , and a base or filler piece 20 of suitable material, such as leather of substantial thickness, is located against the inner face of the casing.

5 This base when in a single piece, as shown in Fig. 3, is provided with a channel 21 to accommodate the inwardly projecting seam, so that the outer face of the filler or base piece 20 lies flat against the inner face of the casing or the canvas lining thereof. The inner face of the base piece is also cut away sufficiently to accommodate projecting parts of the bushing structure or more particularly the washer 14 and shallow flange 16 constituting the outer end of the bushing. The patch 13 and the base or filler piece 20 are then secured firmly in position by a circular row of stitching 22 which surrounds the opening in the casing and crosses the seam 2^a at two points, and amply strengthens and reinforces the seam structure and also the casing opening. The inflation thimble or bushing 10 is thus properly secured in the casing, and the bladder 4 is inserted through the lace-opening; nipple or stem 5 of the bladder is screwed into the bushing, and is then positioned for screwing into it the nozzle of an inflating pump. Normally the tubular bushing is closed by 25 screw plug 25 which enters the nipple 5 and the head of which is substantially flush with the outer surface of the casing.

The base or filler instead of being in a single piece as shown in Fig. 5, may be in two pieces 20^a as shown in Fig. 4, and in that case the inward edges of the filler pieces abut against the outer faces of the inward-projecting seam structure 2^a . The bushing structure and filler pieces are secured to the casing in the same manner, namely, by the circular row of stitching 22.

By the described structure or arrangement the inflation bushing is located at a point diametrically opposite the lace opening 3, and

the ball is thus kept in true rotative balance 45 and at the same time the seam 2^a is reinforced at and about the opening which accommodates the inflation bushing.

I claim:

1. A playing ball comprising a cover having a plurality of sections, the edges of adjacent sections being turned inwardly and secured together by a seam, a filler member secured to the inner side of the cover sections in a position spanning the seam, the 50 filler member being provided with a cut-away portion accommodating the inturned seam edges, the cover and filler being formed with a hole intersecting the seam, and an inflating bushing secured to the inner side 55 of the cover in alignment with the hole.

2. A playing ball comprising a cover having a plurality of sections, the edges of adjacent sections being turned inwardly and secured together by a seam, a filler member secured to the inner side of the cover sections in a position spanning the seam, the 60 filler member being provided with a cut-away portion accommodating the inturned edges, a patch secured on the inner side of the filler member, the cover, filler member, and patch, being formed with a hole intersecting the seam, and an inflating bushing secured to the patch in alignment with the 65 hole.

3. A playing ball comprising a cover having a plurality of sections, the edges of adjacent sections being turned inwardly and secured together by a seam, a filler member secured to the inner side of the cover sections in a position spanning the seam, a 70 patch and an inflating bushing secured thereto, and stitching securing the patch to the inner face of the filler, the filler member being channelled on its face against the cover to accommodate the inturned seam edges.

In testimony whereof I affix my signature.

GEORGE L. PIERCE.
